United States Patent Office

Des. 212,753
Patented Nov. 19, 1968

212,753

DEODORANT CONTAINER

Samuel Tughan, Islington, Ontario, Canada, assignor to
G. H. Wood Company Limited, Toronto, Ontario, Canada, a company

Filed June 29, 1967, Ser. No. 7,650

Claims priority, application Canada Apr. 26, 1967

Term of patent 14 years

(Cl. D23—150)

FIG. 1

I claim:

The ornamental design for a deodorant container, as shown and described.
